(57) **CLAIM**

The ornamental design for a cooking pot pivoting strainer, substantially as shown and described.

DESCRIPTION

FIG. 1 is a right, front side perspective view of the cooking pot pivoting strainer showing the new design;

FIG. 2 is a left, front side perspective view thereof;

FIG. 3 is a rear perspective view thereof;

FIG. 4 is a left side elevation view thereof;

FIG. 5 is a right side elevation view thereof;

FIG. 6 is a top plan view thereof;

FIG. 7 is a front elevation view thereof;

FIG. 8 is a bottom plan view thereof;

FIG. 9 is a rear elevation view thereof;

FIG. 10 is a front perspective exploded view thereof;

FIG. 11 is an illustrative exploded view thereof;

FIG. 12 is a front perspective view thereof while in a raised position;

FIG. 13 is a rear perspective view thereof while in a raised position; and,

FIG. 14 is a bottom, front perspective thereof while in the raised position.

The broken lines shown in the drawings represent environmental matter and form no part of the claimed design.
